I. M. MOORE

LIGHTNING ROD CONNECTER

Filed June 16, 1922

Inventor
Ira M. Moore,
by Geyr Popp
Attorneys.

UNITED STATES PATENT OFFICE.

IRA M. MOORE, OF HAMBURG, NEW YORK.

LIGHTNING-ROD CONNECTER.

Application filed June 16, 1922. Serial No. 568,719.

To all whom it may concern:

Be it known that I, IRA M. MOORE, a citizen of the United States, residing in Hamburg, in the county of Erie and State of New York, have invented new and useful Improvements in Lightning-Rod Connecters, of which the following is a specification.

This invention relates generally to lightning conductors but more particularly to the connecters for joining the lightning rod with the ground or conductor cable which extends along the roof of the building.

Its chief object is to provide a connecter of this character which will produce a strong, perfect and extensive contact with the conductor cable and the lightning rod to insure conducting the lightning to the ground.

A further object is to provide a simple and inexpensive lightning rod connecter which is free from separate fastenings and which can be readily installed.

In the accompanying drawings: Figure 1 is a side elevation of one form of the improvement applied to a conductor cable. Figure 2 is an end view thereof. Figure 3 is a vertical transverse section on line 3—3, Fig. 1. Figure 4 is a plan view of the blank from which said connecter is formed. Figure 5 is a perspective view of a modified form of the invention. Figure 6 is a plan view of the blank for making said modification.

Similar characters of reference indicate corresponding parts throughout the several views.

In both embodiments of the invention shown in the drawings, 10 indicates the lightning rod which is preferably of tubular form and pointed at its upper end, as usual, and 11 the ground or conductor cable fastened at suitable intervals, along the roof and consisting of copper or similar material capable of carrying off atmospheric charges of electricity.

The lightning rod is connected to the cable by the improved connecter which is preferably constructed so that its lower end may be wrapped or folded about said cable, while its upper end is securely joined to the lower end of the lightning rod. To this end, the connecter consists of a vertically-divided tubular body or frame of triangular form, including a base portion 13 split lengthwise on its upper side for receiving

the conductor cable, side portions or legs 14 converging upwardly from the ends of the base portion, and a stem or neck 15 projecting upwardly from the point of intersection 60 of said side portions. The lower end of the lightning rod 10 is adapted to be telescoped over the stem 15. Each half of the body is approximately semi-circular in cross section, so that when the two halves are folded together, a tubular structure is formed 65 whose members are substantially circular in cross section. To reliably and firmly hold the half sections together along their side and base portions, lips or tongues 16, 16^a 70 are employed which project from the edges of one of said sections and are bent around the adjoining sides of the other section, as clearly shown in Figs. 2, 3 and 5. The neck sections of the frame are securely locked together by the slip joint produced by the tubular lightning rod fitting snugly over them. As shown in Figs. 2 and 3, the opposing edges of the frame members meet to 75 form a butt joint when folded together. 80

In the embodiment of the invention shown in Figs. 1-4, inclusive, the connecter body is provided on opposite sides with brace wings 17 for attaching the same to the roof of a building. These wings are preferably 85 formed integral with the body and are triangular in shape. As shown in Figs. 1 and 3, the base-tongue 16^a is stamped out of one of the brace-wings, and is passed through an opening 18 in the other brace wing when the 90 halves of the connecter are brought together.

The connecter so far described is preferably formed from a flat blank of sheet metal, such as copper, of the shape shown in Fig. 4, or approximately so. This blank comprises 95 a central cross portion 19 forming the base portion of the connecter; diagonal oppositely disposed side portions 20 converging outwardly from the ends of said cross portion and adapted to form the side portions 14, and alined extensions 21 projecting from the meeting ends of said side portions and forming the stems 15 of the connecter. Extending from the outer edges of the side portions on one side of the cross portions 19 100 are projections 22 adapted to form the side attaching tongues 16. The blank is provided on opposite sides of the cross portion with substantially V-shaped slits 23 which form the triangular brace wings 17, while a substantially U-shaped slit 24 cut into the body 110 of one of said wings forms the fastening

tongue 16^a. A slot cut in the other wing forms the opening 18 through which said tongue 16^a is adapted to pass.

The modification shown in Fig. 5, differs from the form first described in that the brace wings 17 are omitted. Otherwise, the two forms are identical. In the blank shown in Fig. 6, from which this modified connector is made, the material between the cross bar 19^a and side bars 20^a is cut out, leaving triangular openings 25. Extending from one edge of the cross bar 19^a is a projection 26 adapted to form the base-tongue 16^a of the connector.

This improved connector, while simple and inexpensive in construction, insures a tight, perfect and extensive contact with both the conductor cable and air terminals or lightning rods, affording perfect conductivity from the latter to the ground. Furthermore, as it encloses the cable on all sides, it leaves no objectionable air gaps between the connector and the cable. The integral construction of the device moreover facilitates its installation.

To facilitate the folding of the device about the conductor cable, the metal of the base portion 13 is preferably weakened lengthwise along its bottom, for example by a longitudinal crease, or by a row of openings 27 as shown in the drawings.

I claim as my invention:

1. A lightning rod connector, comprising a vertically-divided foldable frame, including an approximately circular base-portion split lengthwise on its upper side and adapted to be folded about a conductor-cable, opposing side portions extending upwardly from the edges of said base-portion and each consisting of a pair of upwardly-converging leg-sections of semicircular cross section joined at their upper ends by a semicircular neck section, the opposing neck-

sections and leg-sections abutting against each other and forming neck and leg-members of circular cross section when the sides of said base-portion are closed against the conductor-cable, and means for securing said neck and leg sections together. 45

2. A lightning rod connector, comprising a vertically-divided frame including a base portion adapted to be folded about a conductor cable, a head portion adapted to receive a lightning rod, brace wings formed integral with said base portion and extending from opposite sides thereof, and a tongue punched out of one of said brace wings and arranged to be bent around the base portion for drawing it tightly about the cable, the other brace having an opening 50 to receive said tongue. 55

3. A lightning rod connector stamped from a flat sheet metal blank having substantially V-shaped slits located on opposite sides of its center portion, the resulting 65 portions produced by said slits forming brace wings for the connector, and the sides bordering said slits forming outwardly-converging side portions.

4. A lightning rod connector stamped from a flat sheet metal blank having substantially V-shaped slits located on opposite sides of its center portion, and a substantially U-shaped slit located within the area bounded by one of said slits, the area 75 within the other of the last-named slits having a slot, the resulting portions produced by said V-shaped slits forming brace wings for the connector and the portion produced by said U-shaped slit forming a 80 tongue adapted to engage said slot, the sides bordering said V-shaped slits forming side portions, and tongues extending from the outer edges of a pair of said side portions.

IRA M. MOORE.
